UNITED STATES PATENT OFFICE.

JOHN E. CHRISTENSEN, OF CHICAGO, ILLINOIS.

TALKING-MACHINE ATTACHMENT.

Application filed October 16, 1919. Serial No. 330,960.

To all whom it may concern:

Be it known that I, JOHN E. CHRISTENSEN, a citizen of the United States, residing at Chicago, in the county of Cook and State 5 of Illinois, have invented certain new and useful Improvements in Talking-Machine Attachments, of which the following is a specification.

This invention relates to talking machines 10 employing disk records, and its object is to provide a simple and efficient device for facilitating removal of the record from the turn-table of the machine.

The object stated is attained by means 15 of a novel combination and arrangement of parts to be hereinafter described and claimed, and in order that the same may be better understood, reference is had to the accompanying drawing forming a part of 20 this specification.

In the drawing,

Figure 1 is a plan view showing the application 25 of the invention, and

Fig. 2 is a cross section on the line 2—2 of Fig. 1.

Referring specifically to the drawing, 5 denotes the turn-table of a talking machine on which the record disk 6 is supported as usual, the turn-table being carried by a rotatable arbor 7, and having a felt surface insert 8. At the edge of the turn-table is a continuous depending flange 9. The parts thus far described are all of well known construction, and a further description 35 thereof is therefore not deemed necessary.

As the record disk 6 is very thin, some trouble is experienced in its removal from the turn-table 5, and hence a lifting device has been provided by which its removal is 40 greatly facilitated. This lifting device is a lever 10 positioned beneath the turn-table and having at its inner end a head or enlargement 11 which seats in an opening 12 made through the turn-table, so as to lie beneath 45 the record disk. The lever is pivoted, as shown at 13, to a small bracket 13^a mounted on the bottom of the turn-table, and its outer end extends through an aperture 14 in the depending marginal flange 9 of the 50 turn-table, from which latter it projects for

a short distance so that it may be readily grasped. A spring 15, embedded in a recess in the under side of the record disk, bears on the lever and tends to urge the same in a direction to keep its head 11 normally seated in the opening 12 flush with the top surface of the turn-table.

When it is desired to remove the record disk 6 from the turn-table 5, the outer end of the lever 10 is pressed down, which causes 60 the headed end 11 to rise and lift the record disk to a sufficient height so that it may be easily grasped to complete its removal from the turn-table.

It will be noted that the lifting lever 10 65 is supported solely by the turn-table, and as the head 11 is normally retained in the opening 12, the lever is always in position for the lifting operation, and no shifting or adjustment of any parts are necessary.

I claim:

1. The combination with a talking machine turn-table having a depending marginal flange; of a lever pivotally supported by the turn-table on the under side thereof, 75 said turn-table having an opening and the lever having a record-lifting head at one end passing upwardly through the opening, and the flange of the turn-table having an opening through which the other end of the lever extends to project from the exterior of 80 the flange.

2. The combination with the turn-table of a talking machine of the disk-record type; of a lever carried by the under side of the 85 turn-table, and engageable with the record for lifting the same.

3. The combination with the turn-table of a talking machine of the disk-record type; of a lever carried by the under side of the 90 turn-table, the latter having an opening in which the inner end of the lever seats to engage the bottom of the record.

4. In a sound reproducing machine, the combination with a turn-table, of record 95 raising means pivotally supported by said table, and means for operating said first mentioned means.

In testimony whereof I affix my signature.
JOHN E. CHRISTENSEN.
